United States Patent

Des. 234,636
Patented Mar. 25, 1975

234,636

COMBINED FELT-TIP MARKER SET AND CARRYING HOLDER THEREFOR

Joseph A. Burgard, Jr., Newark, Calif., assignor to Primark Corporation

Filed Oct. 13, 1972, Ser. No. 297,231

Term of patent 14 years

Int. Cl. D19—06

U.S. Cl. D19—36

FIG. 2.

FIG. 3.

4FIG. 1 is a perspective view of a combined felt-tip marker set and carrying holder therefor;

FIG. 2 is a top plan view thereof;

FIG. 3 is a front elevational view; and,

FIG. 4 is a perspective view showing one of the modules and associated markers and handle exploded from and in detached relationship with the remainder of the assembled set.

I claim:

The ornamental design for the combined felt-tip marker set and carrying holder therefor, as shown and described.
